UNITED STATES PATENT OFFICE

142,017

DESIGN FOR A HAND MIRROR

Herbert W. Brown, Chicago, Ill.

Application April 20, 1945, Serial No. 119,113

Term of patent 14 years

(Cl. D86—10)

To all whom it may concern:

Be it known that I, Herbert W. Brown, a citizen of the United States, residing at Chicago, in the county of Cook and State of Illinois, have invented a new, original, and ornamental Design for a Hand Mirror, of which the following is a specification, reference being made to the accompanying drawing, forming a part thereof, in which

Fig. 1 is a plan view of a hand mirror embodying my new design, as seen from one face thereof; and

Fig. 2 is an edge elevational view thereof.

The face of the hand mirror opposite that shown in Fig. 1 is similar in design to the face shown.

I claim:

The ornamental design for a hand mirror, substantially as shown and described.

HERBERT W. BROWN.
